DESIGN FOR A DRAINER FOR DISHES

Henry J. Watral, Astoria, N. Y.

Application July 1, 1935, Serial No. 57,479

Term of patent 14 years

To all whom it may concern:

Be it known that I, Henry J. Watral, a citizen of the United States, residing at Astoria, in the county of Queens and State of New York, have invented a new, original, and ornamental Design for a Drainer for Dishes, of which the following is a specification, reference being had to the accompanying drawing, forming a part thereof.

The drawing is a perspective view of a drainer for dishes, showing my new design.

I claim:

The ornamental design for a drainer for dishes as shown.

HENRY J. WATRAL.
